[57] CLAIM

The ornamental design for a pair of interior panels for the rear door of a motor vehicle, as shown and described.

DESCRIPTION

FIG. 1 is a front view of a the left door panel of a pair of interior panels for the rear door of a motor vehicle, showing our new design, it being understood that the right door panel is a mirror image thereof; and,

FIG. 2 is a front perspective view thereof, it being understood that the right door panel is a mirror image thereof.

The broken line showing of environment is for illustrative purposes only and forms no part of the claimed design.
